CLAIM

I claim, the ornamental design for a large lift-up with cover, as shown and described.

DESCRIPTION

FIG. 1 is a perspective view of a large lift-up with cover, according to my design; the opposite perspective view is a mirror image;

FIG. 2 is a front elevational view thereof, the rear elevational view is a mirror image; and,

FIG. 3 is a top plan view thereof.

The broken lines are shown for illustrative purposes only and form no part of the claimed design.
